US00D940563S

(12) **United States Design Patent** (10) **Patent No.:** **US D940,563 S**
Davis (45) **Date of Patent:** **** Jan. 11, 2022**

(54) **DISPENSER**(71) Applicant: **S.C. JOHNSON & SON, INC.**,
Racine, WI (US)(72) Inventor: **Brian T. Davis**, Burlington, WI (US)(73) Assignee: **S. C. Johnson & Son, Inc.**, Racine, WI
(US)(***) Term: **15 Years**(21) Appl. No.: **29/781,734**(22) Filed: **Apr. 30, 2021****Related U.S. Application Data**

(63) Continuation of application No. 29/722,096, filed on Jan. 27, 2020, now Pat. No. Des. 920,802, which is a continuation-in-part of application No. 29/710,489, filed on Oct. 23, 2019, now Pat. No. Des. 920,804.

Primary Examiner — Catherine A Tuttle(74) *Attorney, Agent, or Firm* — Quarles & Brady LLP(57) **CLAIM**

The ornamental design for a dispenser, as shown and described.

DESCRIPTION

FIG. 1 is an isometric view of the top, front, and right side of the dispenser embodying my new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

The oblique line hatching on the cap is indicative of either a transparent or translucent material.
